(57) **ABSTRACT**

The 'WW01' is a hybrid dessert banana variety with a
medium-sized stature, is tolerant to Black Sigatoka, and
produces high-quality fruit.

6 Drawing Sheets

1

Latin name of the genus and species of the plant claimed:
This tetraploid plant has only *Musa acuminata* in its pedigree and is the product of an inter-specific cross between triploid (AAA) plants of the same cultivar. The Latin name of 'WW01' is *M. acuminata*, tetraploid (AAAA), representing four genomes of this genus and species.

Variety denomination:
'WW01'.

**CROSS-REFERENCE TO RELATED
APPLICATIONS**

This application is co-pending with the following additional applications by the same inventor: "DESSERT BANANA PLANT NAMED 'SH-4199'" (application Ser. No. 18/469,772); "DESSERT BANANA PLANT NAMED 'NW02'" (application Ser. No. 18/469,776); "DESSERT BANANA PLANT NAMED 'WH02'" (application Ser. No. 18/469,781); and "DESSERT BANANA PLANT NAMED 'HG07'" (application Ser. No. 18/469,787). The plants of these applications, as well as the plant of the present application, were created in the banana breeding program of Applicant/Owner/Assignee, FHIA.

**STATEMENT REGARDING FEDERALLY
SPONSORED RESEARCH OR DEVELOPMENT**

Not applicable.

BACKGROUND OF THE INVENTION

This invention relates to a new and distinctive hybrid banana variety named 'WW01'. This new hybrid variety was the result of a field cross performed in 2016 in La Lima Cortés, Honduras, between 'Williams' x 'Williams' (Both unpatented). 'Williams' is a medium-sized triploid plant (AAA) susceptible to Black Sigatoka leaf spot disease (*Mycosphaerella fijiensis*), belonging to the Cavendish

2

group. 'Williams' is one of the most commercialized bananas worldwide; people prefer it for its flavor, aroma, and size. This banana was selected from a germplasm collection.

5 'WW01' is a tetraploid hybrid (AAAA) created for the genetic improvement of the Cavendish group banana. This hybrid was selected in 2018 from several first-generation seedlings from the cross between 'Williams' x 'Williams'. It was chosen as a tetraploid hybrid maintaining the "Cavendish type" stature of its female parental line and producing bunches of 20 kilograms with fruits of the same quality as its parents. 'WW01' was asexually reproduced by corms by the breeder in La Lima Cortés, Honduras. All plants and fruit run true to the initially selected plant and are identical in all aspects.

10 15 The hybrid 'WW01' has the same plant as male and female ('Williams'). Its characteristics of plant height, type of leaves, type of stem, and number of offspring are like those of its parents. However, the stem color, bunch type, and taste are different. The 'WW01' hybrid has not inherited the delightful flavor that the 'Williams' variety, belonging to the Cavendish subgroup, is known for. This hybrid has lush foliage, which appears to be more resistant to black Sigatoka than its parents. These comparisons are valid when comparing commercial varieties known to the Inventor because the 'Williams' variety is one of the most commercialized in the world.

BRIEF SUMMARY OF THE INVENTION

20 25 The 'WW01' is a hybrid dessert banana variety with a medium-sized stature, is tolerant to Black Sigatoka, and produces high-quality fruit.

BRIEF DESCRIPTION OF THE PHOTOGRAPHS

30 35 The figures describe the characteristics of the 'WW01' hybrid banana variety. The color shown in the photographs is as nearly accurate as reasonably possible in this type's color representation.

FIG. 1 shows the typical appearance of a plant at ten (10) months old;

FIGS. 2A-B shows blotches at the petiole base (A) and a petiole canal leaf (B);

FIGS. 3A-C shows the shape of a leaf blade base (A) and leaf upper (B) and leaf lower (C) surfaces;

FIG. 4 shows typical suckers;

FIG. 5 shows a typical fruit bunch;

FIG. 6 shows a male bud;

FIGS. 7A-C shows bracts of a male bud;

FIGS. 8A-B shows lobes of compound tepals (A) and free tepals (B);

FIGS. 9A-B shows style shape (A) and ovary (B);

FIG. 10 shows a male flower;

FIG. 11 shows rowed ovules; and

FIG. 12 shows a typical second hand.

DETAILED BOTANICAL DESCRIPTION

The following is a detailed botanical description of the new variety 'WW01'. The report is from ten-month old plants in La Lima, Cortés, Honduras that were evaluated in 2023. The descriptions concord with the internationally standardized "Descriptors for Banana (*Musa* spp.)" elaborated by IPGRI/INIBAP/CIRAD, 1996 (www.inibap.org), and The U.K.'s Royal Horticultural Society's Color Chart, 2001. The 'WW01' plant and its fruit may vary slightly from the detailed descriptors shown below due to cultural practices, soil types, and climatic conditions under which the variety may be cultivated.

-continued

Leaf habit	Drooping	blade on the petiole
Dwarfism	Not shown	The shape of the leaf blade base
Pseudostem length	2.60 meters	Leaf corrugation
Pseudostem width	63 cm	Color of midrib dorsal surface
Pseudostem height	2.1 to 2.9 meters	Color of midrib ventral surface
Pseudostem aspect	Robust	Color of cigar leaf dorsal surface
Pseudostem color	Green (143C, RHS)	Blotches on leaves of water suckers
Pseudostem appearance	Shiny (Not waxy)	Peduncle length
The predominant underlying color of the pseudostem	Green (142D, RHS)	10 Empty nodes on the peduncle
Pigmentation of the underlying pseudostem	Brown (N200A, RHS)	Peduncle width
Sap color	Milky (150D, RHS)	Peduncle color
Wax-on leaf sheaths	Moderately wax	Peduncle hairiness
Number of suckers	3 to 5	15 Number of hands per bunch
Development of suckers	Very good	Bunch length
Position of suckers	Close to parent (vertical growth)	Bunch diameter
Blotches at the petiole base	Extensive pigmentation	Bunch position
Blotches color	Brown (200B, RHS)	Bunch shape
Petiole canal leaf III	Wide with erect margins	Bunch appearance
Petiole margins	Winged and not clasping the pseudostem	Flowers that form the fruit
Wing type	Dry	Fruits
Entire Petiole color	Greyed-purple (187D, RHS)	Rachis type
Petiole margin color	Greyed-purple (187D, RHS)	Rachis position
Edge of petiole margin	Robust and Greyed-purple color (187D, RHS)	Rachis appearance
Petiole margin width	1 to 2 cm	Male bud type
Leaf blade length	171 to 220 cm	Male bud shape
Leaf blade width	71 to 80 cm	Male bud size
Petiole length	40 to 50 cm	20 Bract base shape
Color of the leaf's upper Surface	Green (139A, RHS)	Bract apex shape
Appearance of leaf upper surface	Shiny	Bract imbrication
Color of the leaf's lower surface	Green (139B, RHS)	30 Color of the bract external face
The appearance of the leaf's lower surface	Dull	Color of the bract internal ace
Leaf shape	Oval-elongated	Color of the bract apex
Leaf apex	Obtuse	Color stripes on the bract
Leaf margin	Entire	35 Bract scars on rachis
Wax on leaves	Few waxes	Persistence of the bracts of the rachis
The insertion point of the leaf	Symmetric	Fading of color on bract base
		Male bract shape
		Male bract lifting
		40 Bract behavior before falling
		Wax on the bract
		Presence of grooves on the bract
		Male flower behavior
		Compound tepals per flower
		Compound tepal shape
		45 Upper compound tepal basic color
		Lower compound tepal color
		Compound tepal length
		Compound tepal width
		Compound tepal pigmentation
		50
		Upper lobe color of compound tepal
		Lower lobe color of compound tepal
		55 Lobe development of compound tepal
		Free tepal color
		Free tepal shape
		Free tepal appearance
		60 Free tepal apex development
		Free tepal apex shape
		Anther exertion
		Filament color
		Anther color
		65 Pollen sacs color

-continued

Pollen vitality	Abundant
Style basic color	Greyed-green (198D, RHS)
Pigmentation on style	Without pigmentation
Style exertion	Inserted
Style shape	Straight
Stigma color	Green-white (20B, RHS)
Ovary shape	Arched
Ovary basic color	Green-white (157C, RHS)
Ovary pigmentation	Very few or no visible sign of pigmentation; pigmentation color which is present is light green (149B, RHS)
The dominant color of male flower	White (155C, RHS)
Irregular flowers	Absent
Arrangement of ovules	Two rowed
Fruit position	Parallel to the stalk
Number of fruits	17 to 20
Fruit length	13 to 15 cm
Fruit width	3.5 cm
Fruit shape (longitudinal curvature)	Curved (sharp curve)
Color of the flesh of the fruit	Yellow (9A, RHS)
Longitudinal ridges of the fruit	Moderate
Transverse section of fruit	Rounded
Fruit apex	Bottle-necked
Remains of flower relicts at the fruit apex	Persistent style
Fruit pedicel length	11 to 20 mm

-continued

5	Fruit pedicel width	10 to 12 mm
	Fruit pedicel color	Yellow-green (148A, RHS)
	Pedicel surface	Hairy
	Fusion of pedicel	Very partially or no visible sign of fusion
10	Immature fruit peel color	Green (141D, RHS)
	Mature fruit peel color	Yellow-orange (17B, RHS)
	Fruit peel thickness	1.5 to 2 mm
	Adherence to the fruit peel	Fruit peels easily
	Cracks in fruit peel	Cracked
	Pulp in fruit	With pulp
	Pulp color before maturity	Greyed-white (156C, RHS)
	Pulp color at maturity	White (155A, RHS)
	Fruits fall from hands.	Persistent
	Flesh texture	Firm
15	Predominant taste	Mild, slightly tasty, or tasteless
	Presence of seed with the source of pollen	<5
	Seed surface	Smooth
	Seed shape	Globular (spherical)
	Seed color	Greyed-green (N189B, RHS)
20	Growth habit of the plant	Upright

The invention claimed is:

1. A new and distinct variety of banana plant named
25 'WW01', substantially as illustrated and described herein.
